DESIGN FOR A COMBINATION DRAWING BOARD AND CABINET

Harold S. Boutin, Syracuse, N. Y.

Application March 8, 1937, Serial No. 68,072

Term of patent 14 years

To all whom it may concern:

Be it known that I, Harold S. Boutin, a citizen of the United States of America, residing at Syracuse, in the county of Onondaga and State of New York, have invented a new, original, and ornamental Design for a Combination Drawing Board and Cabinet, of which the following is a specification, reference being had to the accompanying drawing, forming part thereof in which:

Figure 1 is a front perspective view of the combination board and cabinet showing my design, the cabinet being illustrated in open position; and

Figure 2 is a rear perspective view thereof, the cabinet being illustrated in closed position.

I claim:

The ornamental design for a combination drawing board and cabinet as shown.

HAROLD S. BOUTIN.
